J. H. WILHELM

CRIER

Filed July 3, 1926

UNITED STATES PATENT OFFICE.

JOHN H. WILHELM, OF LONG ISLAND, NEW YORK, ASSIGNOR TO MARKON MANUFACTURING CO., INC., OF NEW YORK, N. Y., A CORPORATION OF NEW YORK.

CRIER.

Application filed July 3, 1926. Serial No. 120,341.

This invention relates to sound producing devices for dolls and other toys, and particularly to what is known in the trade as a "crier", that is a device adapted for simulating an inarticulate cry of a young infant, the device being intended to be connected with the doll in such manner that when the doll is moved from one position to another the device will operate to produce a single note 10 cry.

An object of the invention is to provide a crier which may constitute all, or approximately all, of the body portion of a doll, that is one in which little or no covering, or stuffing material, will be required to complete the body or trunk portion of the doll.

A further object is to provide a crier which will make full use of all of the space within a doll body, to the end that the maximum 20 duration and power of cry may be obtained from a given size of body.

A further object is to improve the construction and manner for forming the weight part of the crier.

A further object is to provide a crier which will be durable and efficient in operation, which may be manufactured at low cost and the use of which will result in a material saving in the manufacture of the finished doll.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawings which are to be taken as a part of this specification, and in which I have shown merely a preferred form of embodiment of the invention:—

Fig. 1 is a vertical transverse sectional view through a crier constructed in accordance with this invention, parts of a doll structure being illustrated by heavy dotted lines in association therewith, and

Fig. 2 is a horizontal sectional view taken upon the plane of line II—II of Fig. 1.

Criers as heretofore produced have usually been in such form as to bear little or no resemblance to the contour of the doll's body into which they are to be assembled, the essential object having been merely to make them as small as possible in order to get them into

the doll's body. After they have been placed the space within the body surrounding them has been carefully filled out with a suitable stuffing material as cotton waste, saw-dust, excelsior, or other appropriate material, all 60 of which has been a matter of considerable expense for material and labor in the production of the finished doll.

By the present invention however it is contemplated that the crier may be of such 65 form as to actually comprise the entire doll body, the head, arms and legs being connected thereto in any approved manner either by being attached directly to the material of the crier or to a simple cloth covering stretched 70 over the crier.

To this end the crier as illustrated consists of a shell or body portion L which is of a shape desired for the doll body, or, if intended to be provided with a cloth covering or the 75 like, of approximately the shape of the doll body.

Within this shell is arranged a weight G containing a reed H.

The weight G in the form as illustrated 80 consists of two identical halves as 1 and 2 each half having marginal flange portions 3—3 and a central convexed portion 4—4, the flange portion being flat and arranged to rest flat against opposite surface portions of an 85 interposed diaphragm or bellows cloth 5, the convexed portions 4 being bowed away from each other to thereby provide a central cavity within the weight centrally within which is arranged a partition member 6 dividing the 90 cavity into two separate sound chambers as 7 and 8, there being an aperture as 9 formed through the half 1 communicating with the chamber 7, and a similar aperture 10 formed through the half 2 communicating with the 95 chamber 8.

The partition member 6 has a central opening 11 therethrough made to fit and support the reed H, the reed being held in said opening so that its opposite ends project into the 100 chambers 7 and 8 respectively.

The bellows cloth 5 is held tightly between the flange portions 3—3 of the weight halves and has its entire marginal parts extending to and fixed in clamped relation between telescoping parts as 12 and 13 of the shell, the shell being conveniently formed of two separate members as 14 and 15 connected together by the telescoping parts 12 and 13, said parts occurring approximately on the median line 110

of the shell, and the bellows cloth being sufficiently loose between the weight and its point of engagement between said parts to enable the weight to move freely from side to side 5 of the shell, that is between the positions shown by full and dotted lines in the drawings.

The joint between the parts 12 and 13 is intended to be air tight as is also the bellows cloth itself and the connection thereof with the weight, and the member 14 of the shell is imperforate so that there is thus defined a very efficient bellows for producing a movement of air through the opening 9, chamber 15 7, reed H, chamber 8, and opening 10 whenever the weight gravitates in a direction for collapsing this bellows, that is for moving the weight from the full line position toward its dotted line position in the drawings. The passage of air thus caused will produce sounding of the reed.

The member 15 of the shell is provided with one or more perforations as 16 therethrough through which the sound emanating 25 from opening 10 may pass freely outwardly from the device.

If a covering material, as suggested by the dotted lines 17, is employed, or the doll is provided with cloth clothing, the sound will 30 of course filter through such covering or clothing and be readily audible, whereas if no clothing or like covering is provided, as for instance if clothing is merely painted on to the surface of the shell, the sound will 35 pass directly through the perforations 16 into the open atmosphere, the perforations in this instance being perhaps located to correspond with buttons or other ornamental representations painted upon the shell.

40 The crier described will thus be seen to consist of a bellows and a protecting cover therefor, the bellows being made up of a relatively stationary head 14, a relatively movable weighted head G, and a flexible bellows cloth connecting the two heads, and the protecting cover consisting of the shell member 15 which also serves to connect the bellows cloth with the stationary head of the bellows. The stationary bellows head 14 is cup shaped 50 and constitutes one part or half of the doll body, or at least a supporting frame or foundation for a cloth covering therefor. The protecting cover shell member 15 is also cup shaped and constitutes another part or half 55 of the doll body. And the movable head H is freely suspended between the two cupped body forming shell members.

The particular method shown for connecting together the two halves of the shell and 60 retaining the bellows cloth is suggested merely for the purpose of illustration and it will be understood that other methods of connecting together these parts may be resorted to as may be found most expedient.

65 The manner of connecting together the

two halves 1 and 2 of the movable bellows head G may take any desired form. For the purpose of the present description however a simple method of connection is shown which consists in first placing together the 70 two halves 1 and 2, with the bellows cloth interposed between them, and the partition member 6 and reed H likewise being held between them, and then punching, with a suitable punch press, portions of the two 75 halves so that portions 18-18 of one of the halves will stand partly within the punch hole of one half and partly within the punch hole of the other half. The portions 18 thus serve as a bond between the two halves. The 80 friction grip of the portions 18 upon the two halves is very great when produced in this manner and holds the halves in tight clamping engagement with the interposed bellows cloth, and likewise with the interposed partition member 6 so that said partition member, and its reed, are held by the same operation.

By so constructing the device that the reed H has its opposite ends projecting into the separate and distinct chambers 7 and 8 both 90 of said chambers are made to serve as sound chambers, which materially increases the volume and improves the quality of sounds ultimately produced.

It will be apparent from the above that 95 the full extent of the interior of the doll body is utilized as, or for containing, the crier, and that hence the fullest possible duration and power of cry may be obtained in any given size of body, which is a matter 100 of prime importance particularly in that a satisfactory duration and power of cry may be provided in doll bodies considerably smaller than heretofore.

As many changes could be made in this 105 construction without departing from the scope of the invention as defined in the following claims, it is intended that all matter contained in the above description or shown in the accompanying drawings, shall be interpreted as illustrative only and not in a 110 limiting sense.

Having thus described my invention, what I claim as new and desire to secure by Letters Patent is:—

1. A doll comprising a body member consisting of a hollow shell, a gravity movable weight within said shell, a bellows cloth connected directly with said shell and weight to support the weight and to permit free movement of the weight within the shell to thereby displace air, the weight being hollow and having openings by which the displaced air may flow therethrough, and a reed mounted within the hollow of the weight arranged to be operated by the displaced air.

2. A sound producing device for dolls, said sound producing device comprising a bellows made up of a relatively stationary head, a relatively movable head, and a bel-

- lows cloth connecting the movable head with the stationary head, the stationary head being cup shaped, the bellows cloth being connected with the movable head and extending 5 radially therefrom in all directions having its marginal portion connected with the marginal portion of the stationary head so that the movable head is suspended from the stationary head by means of said bellows cloth, the bellows cloth constituting the sole 10 guide and support for the movable head and being free to permit unobstructed movement of the movable head into and out of the stationary head for displacing air from said stationary head, a reed arranged to be 15 operated by the displaced air, and a second cup shaped member corresponding in size and contour to the first cup shaped member having its marginal portion telescoping over the marginal portion of the first cup shaped member serving to connect the two cup shaped members together and to fix the bellows cloth to the first cup shaped member, the second cup shaped member being perforate and said two cup shaped members thus constituting a protecting shell within which the weight is suspended by the bellows cloth 25 at the median line of the shell.
3. A sound producing device for dolls, said sound producing device comprising a bellows made up of a relatively stationary head, a relatively movable head, and a bellows cloth connecting the movable head with the stationary head, said movable head comprising a pair of convexed members connected together by their marginal portions so as to provide a cavity between them, a partition member in said cavity dividing the cavity into two sound chambers, there being means 30 affording connection between one of said sound chambers and the interior of the bellows and between the other sound chamber and the exterior of the bellows, and a reed supported by said partition member having its opposite ends in communication with said sound chambers respectively. 45
4. A sound producing device for dolls, said sound producing device comprising a bellows made up of a relatively stationary head, a relatively movable head, and a bellows cloth connecting the movable head with the stationary head, said movable head comprising a pair of convexed members connected together by their marginal portions so as to provide a cavity between them, portions of the bellows cloth being positioned between the marginal portions of said convexed members and being held in clamped engagement between said members, there being means 50 providing for a passage of air from within the bellows outwardly to the atmosphere through said cavity, and a reed in said cavity arranged to be sounded by the passing air. 55
5. A sound producing device for dolls, said sound producing device comprising a bellows made up of a relatively stationary head, a relatively movable head, and a bellows cloth connecting the movable head with the stationary head, the relatively movable 60 head consisting of a pair of flanged members arranged in parallel relation and with their flangeslapping each other with portions of the bellows cloth interposed between them, a part of the flange of one of said members being partly punched out therefrom and projected into a recess of the flange of the other member to thereby frictionally connect said members together and hold the bellows cloth connected with said members, there being 65 means providing for a passage of air from within the bellows outwardly to the atmosphere through said members, and a reed carried by said movable head arranged to be operated by the passing air. 70
